FUSIBLE PROTECTIVE DEVICE

Merrill G. Leonard, Brookfield Township, Trumbull County, Ohio, and John J. Astleford, Jr., Sharon, Pa., assignors to Westinghouse Electric Corporation, Pittsburgh, Pa., a corporation of Pennsylvania

Filed Dec. 26, 1961, Ser. No. 162,144

15 Claims. (Cl. 200—120)

This invention relates to fusible protective devices in general, and, more particularly, to fusible protective devices of the type utilizing a plurality of fuse links in series for clearing the associated circuit.

A general object of the present invention is the provision of an improved fusible protective device particularly suitable for the efficient clearing of the associated circuit and of economical construction for mass production.

A more specific object of the present invention is the provision of an improved two-break fusible assembly particularly adaptable for interrupting a wide range of currents.

A further object of the present invention is to provide an improved protective device of the fusible type suitable for immersion in an arc-extinguishing liquid, such as oil, and highly efficient in operation.

Yet a further object of the present invention is the provision of a suitable fusible protective device applicable to oil-immersed distribution transformers, such, for example, as those having a 167 kva. rating, which will clear high-value fault currents, such, for example, as 10,000 amperes at 12,000 volts.

Still a further object of the present invention is the provision of a two-break fuse assembly of the oil-immersed type, in which two breaks in series are established, with one break forcing oil to flow under pressure toward the other series break for a short clearing time.

Yet a further object of the present invention is the provision of an improved fusible assembly involving few parts and adapted for facilitated fabrication.

An ancillary object of the present invention is the provision of an improved fusible protective device having biasing means, such, for example, as spring means associated therewith for the rapid interruption of low-value currents, and having two series fusible elements for establishing two fusible breaks in the circuit, whereby one of the fusible breaks preferably forces fluid to flow toward the other fusible break for rapid interruption.

Although certain features of the present invention are particularly adaptable for distribution transformer use, involving oil as the arc-extinguishing liquid, nevertheless, it will be apparent to those skilled in the art, that certain features of the present invention are applicable to other arc-extinguishing mediums than oil; and, accordingly, the improved fuse structure of the present invention may be applied, when desired, to gas-filled enclosures, or even utilized in an air ambient at atmospheric pressure.

Further objects and advantages will readily become apparent upon reading the following specification, taken in conjunction with the drawings, in which:

FIGURE 1 is a fragmentary vertical sectional view, partially in side elevation, and partially diagrammatic, of the improved fusible protective device of the present invention utilized in a subway distribution transformer tank-assembly of the oil-filled type;

FIG. 2 is an enlarged fragmentary side elevational view of the connection between the fusible device of the present invention and the interior projecting stud end of the pot-head assembly for the tank structure of FIG. 1;

FIG. 3 is a vertical longitudinal sectional view taken through the fusible assembly of the present invention with the series fuse elements shown in their intact condition;

2

FIG. 4 is a top plan view of the fusible protective device of FIG. 3;

FIG. 5 is a detailed end elevational view of the insulating orifice plug utilized in the fuse casing assembly;

FIG. 6 is a side elevational view of the insulating orifice plug of FIG. 5;

FIG. 7 is an enlarged detail side elevational view of the two-break fusible assembly of FIG. 3 illustrated in its intact condition;

FIGS. 7A and 7B illustrate cross-sectional views taken through a modified-type two-break fuse assembly, wherein one fuse element is larger than the other fuse element;

FIGS. 8 and 9 are sectional views taken respectively along the lines VIII—VIII and IX—IX of the fuse assembly of FIG. 7;

FIG. 10 is a view similar to that of FIG. 3, but illustrating the condition of the several parts upon fuse rupture;

FIG. 11 illustrates, in vertical cross-section, a modified-type two-break fusible protective device, the fuse elements being illustrated in their intact condition;

FIG. 12 is a vertical sectional view, similar to that of FIG. 11, but illustrating the disposition of the several parts upon fuse rupture; and,

FIG. 13 is a graph showing clearing time as a function of current for the device of FIG. 3.

Referring to the drawings, and more particularly to FIG. 1 thereof, the reference numeral 1 generally designates a subway distribution transformer tank-assembly

30 having an interiorly-disposed transformer 2 associated therewith. As shown, the transformer 2 is submerged in transformer oil 3, and has a pothead assembly 4 associated therewith.

Fixedly secured to the lower interior end 5 of the pot-

35 head assembly 4 is the protective device 7 of the present invention partially enclosed by an insulating support tube

10. It will be noted that the electrode 8 of a fuse assem-

30 bly 9 (FIG. 3) is threadedly secured to the interior end

11 of the stud-assembly associated with the pothead 4.

40 FIG. 2 illustrates more clearly the associated threaded relationship of the stud 11 with the electrode 8.

With reference to FIG. 3 of the drawings, it will be ob-

35 served that there is provided an insulating casing 12 of generally tubular construction. The casing 12 preferably

45 has three shoulder portions 13—15 formed along the inner wall thereof. Additionally, the insulating fuse casing 12 is preferably formed of a suitable gas-evolving material,

such as fiber, or the like.

The electrode 8 of the fuse assembly 9, as shown, has a

50 pair of axially-aligned threaded recesses 16, 17. The threaded recess 16 is adapted for threaded connection to the stud 11, as previously mentioned. The threaded

55 recess 17 is adapted to threadedly receive a stud 18 (FIG. 7) associated with a two-break fusible device, gen-

erally designated by the reference numeral 9, and shown

more in detail in FIGS. 7—9 of the drawings.

With reference to FIG. 7, it will be noted that the stud

50 18 has a connecting portion 18a, to which is secured, as

60 by brazing, an inner, or first fusible element 22, of round,

wire-like configuration, as shown in the sectional view of

65 FIG. 8. Although shown as round wire-like configura-

70 tion, the fusible element 22 could have other cross-sec-

tional configurations, such as square, or rectangular, as

65 desired.

To the lower end of the fusible element 22, as viewed

70 in FIG. 7, is secured, as by brazing, a substantially U-shaped connector 23 preferably of strap-like configura-

75 tion. As shown in FIG. 7, the connector 23 preferably

70 has fixedly secured thereto, as by brazing, a stop element

75 24. Preferably, the connector element 23 and the stop

80 element 24 are formed of a suitable metallic material,

such, for example, as copper strap. For one partic-

ular application, the connector 23 may be formed of $3\frac{1}{32}$ " x $\frac{3}{8}$ " of .063" thick copper strap. The stop element 24 may be formed of similar strap material.

Fixedly secured, as by brazing, to the lower end of the connector element 23, as viewed in FIG. 7, is an outer, or second fusible element 27, having a configuration and size similar to that of the first-mentioned fusible element 22. For example, the fusible elements 22 and 27 may be formed, for example, of .064" round fusible wire. To obtain selective melting, the first fuse link 22 is shorter in length "l" than the second fuse link 27, the length of which is indicated by "L," as shown in FIG. 7. For a particular example, the length "l" may be $\frac{3}{8}$ " whereas the length "L" may be $\frac{5}{8}$ ". As a result, for relatively low-value fusing currents, the element 27 may be the only one to melt, whereas on larger fusing currents both elements 22, 27 will fuse substantially simultaneously creating two breaks in the circuit.

Fixedly secured to the lower end of the outer, or second fusible element 27 is a fuse ferrule 28, the lower end of which, in turn, is fixedly secured to a conducting cable 30.

As shown in FIG. 3, the flexible conducting cable 30 has a cup-washer 31 threaded thereon and secured thereto by a crimping connection 32. Interposed between the cup-washer 31 and the shoulder portion 15 of the tubular casing 12 is a biasing compression spring 34, which serves the purpose of maintaining the fusible assembly 9 and the fusible elements 22, 27 thereof in tension.

During a heavy fault-current condition upon the line to be protected, as mentioned, the two fusible elements 22, 27 of the fusible assembly 9 will rupture, forming thereby two breaks in series, as illustrated in FIG. 10 of the drawings. It will be noted that a first, or pressure-generating break 35 is formed between the remaining ends of the first fusible element 22, whereas a second, or interrupting break 36 is formed between the ends of the outer, or second interrupting fusible element 27. A blast of fluid is ejected under pressure from the first break 35 toward the second break 36, as indicated by the arrows 20 in FIG. 10. Where, in the particular application, oil 3 is the interrupting medium, it will be obvious that a blast of un-ionized oil particles will be ejected toward the second break 36. In addition, the action of the biasing compression spring 34 will be effective to accelerate the opening separating movement of the second, or interrupting break 36.

For certain applications it may be desirable to have the cross-sectional area of the inner, or first fusible element 22 somewhat larger than the cross-sectional area of the second fusible element 27. This state of affairs is illustrated in FIGS. 7A and 7B of the drawings, which respectively are cross-sectional views taken through a modified-type of fusible assembly 9a, wherein the respective cross-sectional areas of the fuse elements 22a, 27a have the aforementioned relative dimensions. As a result of such a modified construction, the second fusible element 27a would tend to rupture first at relatively low currents, and possibly might be the only fusible element of the assembly 9a to rupture. For higher-value currents, both elements 22a, 27a would rupture; and the interrupting action would take place as in the first-mentioned embodiment 9 of FIG. 3 of the drawings.

FIGS. 11 and 12 illustrate a fusible modification 49 of the invention wherein a fuse casing 50 has a bore extending therethrough and threaded end portions 50a, 50b. Threaded into the upper end of the fuse casing 50 is a terminal plug 48, which closes this end of the casing 50. A connector strap 48a may be affixed by a terminal bolt 48b to the upper terminal 48 to serve as a connection to the circuit to be protected.

Threaded into the lower end 50b of the tubular fuse casing 50 is an orifice plug 51 having an aperture 52 therethrough. It will be noted that a pellet 53 is attached to the fuse cable 54, so that the pellet 53 may be subjected to the gas pressure and ejected out of the casing 50 during

the interrupting operation. In effect, therefore, a pressure-generating chamber 60 is provided interiorly of the fuse tube 50, and pressure generated therein during fuse rupture. Preferably, the top fusible element 70 is of a slightly larger cross-sectional area than the lower fusible element 71 so that at relatively low-value fusing currents the lower fusible element 71 will be the only one to rupture. For higher fusing current levels, both fusible elements will rupture, thereby causing a blast of fluid, such as oil, from the upper, or inner arc 80 to be ejected toward the second, or outer arc 81, as illustrated more clearly in FIG. 12 of the drawings.

Preferably, the tubular fuse casings 12, 50 of the various embodiments are formed of a gas-evolving material, such as fiber or the like. In addition, the apertured orifice plugs 6, 51 are likewise formed of gas-evolving material, such as fiber for more efficient arc-extinguishing action.

From the foregoing, it will be apparent that the present invention relates to a new type of protective link 7, 49 for more powerful arc-extinguishing action, particularly when the protective link is disposed in an oil ambient. It is believed that a basic new feature of the invention, as illustrated in FIGS. 11 and 12, is a three-section wire, the top section 70 being slightly larger than the bottom section 71, and the central section 75 being much larger than either of the aforesaid sections 70, 71. For certain applications, as illustrated in FIGS. 11 and 12, an ejectable pellet 53 is a free fit within the apertured fiber orifice 51.

In the operation of the modified form of the invention illustrated in FIGS. 11 and 12, the interrupting operation during low-value currents causes the lower section 71 to blow first, thereby drawing an arc 81 inside of the fuse orifice 51. For minimum fusing current, this suffices to clear the circuit. For higher current levels, the upper, or inner section 70 blows an instant after the lower section 71. This causes an arc 80 at the inner section, which during expansion drives oil 3 around the outer, or lower fusible element 71 and out through the fuse orifice opening 52. The result is a double-gap construction to quench the arc, plus forced oil flow through one of these gaps. The forcible ejection of the pellet 53, attached to the fuse cable 54, further aids in arc extinction.

It is to be noted in the construction of FIGS. 11 and 12, that the intermediate fuse section 75 is not only much larger in cross-sectional area than the first and second fuse elements 70, 71, but preferably is flat or ribbon-shaped in configuration so that it will not clog the orifice tube 51. It is believed that novelty resides, in part, concerning the combination in a fuse of a double-break, forced fluid flow, such as oil flow, through the arc 81 in the orifice 52, and free travel of a bottom electrode 53 through an arc-extinguishing medium, such as oil 3, below the fuse structure 49.

Remarkable interrupting results have been achieved with the fuse structure 7 illustrated in FIGS. 3-9 of the drawings. Successful interruption tests at 12 kv. were made on a 10,000-ampere protective link.

FIG. 13 illustrates, in graphical form, the aforesaid interrupting tests. It will be apparent that the time, as a function of current to be interrupted, can be carefully controlled to the desired time values.

Although certain features of the present invention have particular application when utilized in connection with a suitable arc-extinguishing liquid, such as oil, nevertheless it will be apparent to those skilled in the art that other suitable arc-extinguishing mediums, such as sulfur-hexafluoride (SF_6) gas, selenium-hexafluoride (SeF_6) gas, sulfur, etc., or even air at atmospheric pressure may be employed.

Although there have been illustrated and described certain specific fuse structures, it is to be clearly understood that the same were merely for purpose of illustration, and that changes and modifications may readily be made by

those skilled in the art, without departing from the spirit and scope of the invention.

We claim as our invention:

1. A fusible device including a tubular casing having an electrode assembly blocking one end thereof, the other end of said tubular casing being open, a unitary two-break fuse assembly disposed within the casing and including a pair of spaced fusible elements, an orifice plug fixedly secured against said open end of the casing, biasing means for tensioning both the pair of fusible elements of the fuse assembly, and conducting spacing means associated with the two serially-related fuse elements having stop means associated therewith to limit the length of one of the arcs.

2. The fusible device of claim 1, wherein one of the fusible elements has a smaller cross-sectional area than the other.

3. The fusible device of claim 1, wherein one of the fusible elements is positioned adjacent the orifice plug and is suitable dimensioned to fuse before the other serially-related fusible element during low-value fusing currents.

4. The combination of claim 1, wherein the conducting spacing means is substantially U-shaped so as not to block the open end of the casing.

5. The fusible device of claim 1, wherein a fuse cable is secured to the fuse assembly and extends out the open end of the casing.

6. The combination according to claim 5, wherein the biasing means comprises a compression spring seated on a spring seat secured to the fuse cable.

7. The combination according to claim 1, wherein one of the fusible elements is of greater length than the other.

8. A fusible device including a generally tubularly-shaped casing at least partially of insulating material, means closing one end of said casing, the other end of said casing being at least partially open, terminal means disposed adjacent said one end of the casing, unitary double-break fusible means positioned at least partially within said casing and having one end thereof electrically connected to said terminal means, said fusible means including a pair of spaced fusible elements, biasing means associated with said other end of the casing and tensioning said unitary double-break fusible means as a unit to an open-circuit condition, and stop means associated with said spaced fusible elements to limit the length of one of the established arcs.

9. In combination, a fusible device adapted for the protection of transformers, or the like, including a tubular casing, electrode means closing one end of the casing, the other end of the casing being open, tensioning means situated adjacent said other end of the casing, a unitary two-break fuse assembly disposed within the casing and including a pair of spaced fusible elements and an inter-

vening conducting spacing means, said tensioning means acting to tension both elements of said double-element fuse assembly, and stop means associated with the intervening conducting spacing means to limit the length of one of the arcs.

10. The fusible device of claim 9, wherein one of the pair of spaced fusible elements is disposed adjacent the open end of the casing and is so dimensioned so as to fuse before the other serially-related fusible element during low-value fusing currents.

11. The fusible device according to claim 8, wherein one of the spaced fusible elements is situated adjacent the open end of the casing, and said one fusible element is so dimensioned so as to fuse before the other serially related fusible element during low-value fusing currents.

12. A fusible device including a generally tubularly-shaped casing at least partially of insulating material, means closing one end of said casing, the other end of said casing being at least partially open, terminal means disposed adjacent said one end of the casing, unitary double-break fusible means positioned at least partially within said casing and having one end thereof electrically connected to said terminal means, said fusible means including a pair of spaced fusible elements, and stop means associated with the spacing means for said pair of spaced fusible elements to limit the length of one of the established arcs.

13. The combination according to claim 12, wherein a pellet (53) attached to the fusible means is disposed within the open end of the casing so as to be subjected to gas pressure and thereby assist the fusing operation.

14. The combination according to claim 12, wherein one fusible element is so dimensioned as to fuse before the other serially-related fusible element during low-value fusing currents.

15. The combination according to claim 12, wherein one of the fusible elements is positioned adjacent the open end of the casing and is of greater length than the other fusible element.
